UNITED STATES PATENT OFFICE

163,169

BICYCLE TANK OR SIMILAR ARTICLE

Jack Daugherty, Chicago, Ill., assignor to Monark Silver King, Inc., Chicago, Ill., a corporation of Delaware

Application February 23, 1950, Serial No. 8,085

Term of patent 14 years

(Cl. D90—1)

To all whom it may concern:

Be it known that I, Jack Daugherty, a citizen of the United States, residing at Chicago, county of Cook, and State of Illinois, have invented a new, original, and ornamental Design for a Bicycle Tank or Similar Article, of which the following is a specification, reference being had to the accompanying drawing, forming a part thereof, in which:

Figure 1 is a perspective view of a bicycle tank or similar article, showing my new design; Fig. 2 is a top plan view; Fig. 3 is a side elevational view; Fig. 4 is a rear elevational view; and Fig. 5 is a front elevation view thereof.

I claim:

The ornamental design for a bicycle tank or similar article, as shown.

JACK DAUGHERTY.
